SHUTTER CONSTRUCTION

Casimir J. Wood, Hillsborough, Calif., assignor
to Redwood Manufacturing Co., Pittsburg,
Calif., a corporation of Nevada

Application April 8, 1941, Serial No. 387,404

5 Claims. (Cl. 20—62)

This invention relates to shutters or blinds of the type having louver blades pivoted at their ends for swinging to open or closed position.

One of the objects of this invention is a shutter having such blades, and so constructed as to seal the opening in which the shutter is positioned against entry of wind or rain into the room in which such opening is located, and which shutter is adapted to be opened to various degrees for ventilation, and when only partially open, will materially lessen the amount of moisture that would otherwise pass through said opening, under similar circumstances, where a conventional structure is employed.

Another object is a shutter that is easy to make and to install, and which includes means for easily and quickly operating all or a predetermined number of the louver blades simultaneously, and which blades are constructed to interlock with each other when fully closed, to form a joint between adjacent blades having a tortuous cross-sectional contour for obstructing the passage of water or moisture between adjacent blades.

Other objects and advantages will appear in the following specification and in the drawings.

In the drawings,

Fig. 1 is an elevational view of my shutter as seen from outside the wall opening in which it is adapted to be positioned.

Fig. 2 is an edge view of the shutter of Fig. 1 in the frame carrying the blades.

Fig. 3 is an enlarged sectional view taken along line 3—3 of Fig. 1.

Fig. 4 is a sectional view taken along line 4—4 of Fig. 1, but partially broken in vertical length to accommodate the view to the sheet.

Fig. 5 is a sectional view showing the relation between the overlapping margins of several louver blades when the blades are in partially open position.

Fig. 6 is a fragmentary sectional view showing a form of the invention in which the shutter blades are in several gangs for separately opening of one or more gangs of blades as desired.

In detail, the shutter comprises a rectangular frame having a sill 1, head piece 2, and side pieces 3. This frame may be fixedly secured in the wall opening, or may be removably supported in an existing frame in such opening. Below the horizontal head piece 2 is a horizontally extending upper strip 4 secured to said head piece, and above sill 1 is a somewhat similar lower strip 5 secured thereto. Strips 4, 5 extend the full distance between side pieces 2.

Between strips 4, 5, is a vertical row of horizontally extending, parallel louver blades 6, said blades extending substantially the full distance between side pieces 2. Each of said blades is pivoted at its opposite ends by any suitable, horizontally aligned, horizontal pivots 7, to side pieces 3.

Referring to Fig. 4, the louver blades are shown in fully closed position in full line and in open position in dotted line. The inner sides of the blades face into the room and the outer sides face outwardly therefrom. The blades are substantially uniform in width, and each blade is recessed from its elongated free edge a uniform distance at opposite sides of the medial plane of the blade to provide an upper flange 8 along the upper edge thereof and a lower flange 9 along the lower edge. These flanges 8, 9 are offset at opposite sides of the medial plane of each blade, and the blades are positioned so that the lower flange 9 of each blade overlies the upper flange 8 of the next blade therebelow. Strips 4, 5 are similarly recessed along their lower and upper edges respectively to form flanges 12, 13 that correspond, respectively, to the lower and upper flanges of a blade, and which flanges 12, 13 are adapted to engage the sides of the upper and lower flanges 8, 9, respectively, of the upper and lower blades in the row of said blades. The flanges 8, 9, 12, 13 are preferably generally planar with the plane of the row of blades when the latter are in closed position, and when the blades are in said closed position, the flange on each blade fits in the recess formed along the longitudinal edge of the blade adjacent thereto, while the upper flange of the upper blade, and the lower flange of the lower blade, respectively fit in the recess in the lower edge of strip 4 and in the upper edge of strip 5. The flange 9 on each blade is adjacent the outer side of each blade while the flange 8 is adjacent the inner side of each blade, and flange 12 is adjacent the outer side of strip 4 while flange 13 is adjacent the inner side of strip 5, hence, when the blades are in closed position, any rain striking the blades or strip 4, will drain downwardly over the blades and said strip, including strip 5, and cannot pass between the blades or between the blades and strips 4, 5 without passing upwardly between the adjacent sides of flanges 8, 9 or between the flanges 8, 12 and flanges 9, 13 and then passing generally horizontally again over the uppermost edges of flanges 8, 13. The uppermost edges of flanges 8, 13 and the side of the recess in the lower edge

of the blade or strip next above, are inclined slightly downwardly from the inner toward the outer sides of the blades and strip, while the lowermost edges of flanges 9, 12 and the sides of the recess in the upper edge of the blade or strip therebelow are similarly inclined so as to even more surely prevent moisture passing into a room through the shutter when the blades are in closed position.

In the foregoing description and claims, the term "upper" and "lower" refers to the edges of the blades or strips 12, 13, respectively, that are uppermost or lowermost when the shutter is substantially closed or fully closed, as indicated in Fig. 4.

The flanges 8, 9, 12, 13 extend the full lengths of the blades 6 and strips 4, 5. About centrally of the width of each flange 8 and flange 13, is a ridge 10 extending the full length of each such flange, and these ridges are preferably substantially rectangular in cross-section. In each flange 9 and flange 12 is formed a channel or groove 11 (Fig. 5) corresponding in cross-sectional contour to the ridges 10 and which channels or grooves are positioned about centrally of the width of each such flange to receive the ridges 10 on the flanges 8 and strip 13 when the shutter blades are closed. This construction provides joints of tongue and groove structure between adjacent flanges, thus positively preventing the passage of moisture past such joints even under the most severe weather conditions.

All of the louver blades are connected for pivoting simultaneously on pivots 7 to similar positions between vertical (closed) and horizontal (open) positions, by means of vertical strips 14 respectively positioned next to the inner sides of side pieces 3. A right angle bracket may connect each end of each blade to one of said strips, one leg 15 of each bracket being connected by a pivot 16 with a strip 14 and the other leg 17 being connected by screws 18, or by any other suitable means to an end of each blade. The pivots 16 are equally spaced apart and are equally spaced from the pivots 7 of the blades to which they are secured. When the blades are in closed position, the side of each strip facing the blades is close to the inner sides of said blades and substantially in engagement with said inner sides. The said side of each strip is formed with a tongue 19 extending longitudinally thereof and the inner sides of said blades adjacent the ends thereof are formed with grooves 20 in vertical alignment, which grooves receive said tongues when the blades are in closed position (Fig. 3). In this manner, the means for opening and closing the shutter, in combination with the shutters, forms a tongue and groove sealing joint at the ends of the shutters, so that any rain that might pass between the ends of the blades 6 and side pieces 3, and then between the adjacent side of strips 14 and said blades and into the room, is obstructed by the tongue and groove joint formed by tongues 19 and grooves 20.

Along the edges of strips 14 that are opposite tongues 20, each strip is formed with a flange 21 (Fig. 3) that carries a vertically extending tongue 22 that projects toward the outer side of the shutter, and the inner edge of each side piece 3 is formed with a groove 24 that receives the tongue 22 on the strip adjacent thereto, when said shutter blades are in closed position. Thus, a tongue and groove joint is provided between each strip 14 and each side piece 3 that obstructs passage of water into the room, which water would other-

wise pass between the ends of the blades and said side pieces and then between the strips 14 and said side pieces into the room. In fact this point is a double tongue and groove joint, since a groove 23 between tongue 22 and the main portion of strip 14 receives a tongue 25 formed on the inner edge of the side piece 3 between groove 24 and the side of the side piece adjacent the ends of the blades 6.

The strips 14 terminate at their lower ends short of the sill 1 when the blades are in closed position, so this space between the lower of the strips and sill, is closed by stationary strips 26 secured to side pieces 3. These strips 26 are substantially downward continuations of strips 14 when the blades 6 are closed, but are relatively narrow to insure clearance for strips 14 when the strips are pivoted to open the shutter.

In referring to grooves 20, it is pertinent to note that upper strip 4 is grooved in continuation of said grooves and likewise, lower strip 5 has grooves in continuation of grooves 20. The strips 26 are formed with tongues respectively fitting in each of the said grooves in said lower strip and which tongues also fit in the grooves 20 in the lower louver blade of the row of blades. Furthermore, the upper strip 4 has a tongue 27 on its upper edge fitting in a groove in the head piece 2, while strip 5 is formed with a tongue 28 fitting into a groove in sill 1, and downwardly directed passageways P (Figs. 2, 3) may be formed in said sill opening at the upper ends thereof into the room adjacent the inner side of strip 5 and outwardly of said strip at the lower ends, to permit drainage of any moisture from the inner side of the shutter structure that may enter when the louver blades are partially or fully open. While these passageways may be formed in the strip 5 itself at its lower edge, it is preferable that they open outwardly of the blades below said sill, so as to positively insure against any moisture being driven therethrough from outside the wall in which the shutter is mounted.

The head piece 2 and sill 1, form stops limiting the swinging of strips 14 to positions in which the blades 6 are closed or open, thus insuring against excessive strain on the blades, although the strips 14 will engage the inner sides of the blades at the upper end of their stroke when closing the shutter.

Secured to sill 1 is a right angle bracket 29, one leg of which is secured to the sill adjacent one of side pieces 3, while the other leg carries a pivot 30 that pivotally secures one end of a link 31 thereto. This link is elongated, and is formed with a slot 32 therein extending longitudinally thereof. A bolt 33 secured to the strip 14 adjacent thereto extends through said slot, said bolt being provided with a wing or thumb nut 34 that is adapted to releasably clamp the link to the bolt against movement in any position of strips 14 in their stroke from and to positions in which the shutter is fully open or closed.

The side pieces 3 may be vertically grooved alongside strips 14, as indicated at 35 (Fig. 3), and also outwardly of blades 6 as indicated at 36, so as to drain to the sill 1, any moisture driven against the side pieces or such moisture as may be driven along the louvers to said side pieces. Since the grooves 36 are scanned by the end edges of the louver blades when the latter are swung upon on their pivots 7, any moisture driven along the blades to their ends will drain into the grooves for passage to the sill, when the louvers are partially or fully open.

The strips 14 are connected together intermediate their ends by a connecting bar 38, which bar secures said strips together in spaced relation for simultaneous movement in their stroke for swinging the blades 6, and said bar also functions as a handle to be grasped by an operator for so swinging the blades.

It is pertinent to note that when the blades 6 are only partially open, as indicated in Fig. 5, a tortuous passage is formed between the opposed flanges of the adjacent blades through which air must pass in entering a room. This tortuous passage will admit air to the room, but greatly restricts the amount of moisture that may be carried by the air, since eddy currents will be set up between said flanges to cause the moisture to be deposited on said flanges, and even when the louver blades are fully open, the moisture that is deposited on the upper surfaces of the blades will not be driven across the tongues 10 into the room, but will be stopped by said flanges for drainage off the ends of the blades to the sill and then back to outside the sill.

Referring to Fig. 6, I show a shutter in which the blades 6 are in two gangs, the blades of the upper gang being connected at their ends to strips 14a and the blades of the lower gang being connected at their ends to strips 14b. These strips and their connections with the blades, being substantially the same as already described with respect to strips 14.

The lower blade of the upper gang overlaps the upper blade of the lower gang to form a continuous row of blades identical with that shown in the previous figures.

A cross bar 38a connects strips 14a for actuating the blades of the upper gang, and a cross bar 38b similarly connects the strips 14b.

To insure movement of the upper strips 14a to positions clearing the upper ends of strips 14b, it is necessary that the upper portions 26a of the lower strips be materially reduced in width.

The upper and lower strips 14a and 14b, are connected at their adjacent ends by a link 31a that is pivoted at its lower end to strip 14b by a pivot 30a, while the upper strip 14a carries a bolt extending through the slot 32a in said link. When the upper and lower gangs of blades are closed, and the wing nut 34a on bolt 33a tightly clamps the strips 14a and 14b against relative movement, it will be seen that the two gangs of shutters may be operated in exactly the same manner as the shutter previously described herein. However, when the nut 34a is loosened, then the upper gang of blades may be opened, and the lower gang closed, or vice versa, or each gang may be opened to different degrees, as desired.

While this invention is termed a window shutter, and may be readily formed from wood, metal, or composition material, it is pertinent to note that where the louver blades are made of transparent or light transmitting material such as glass, or moldable material designated generally in the trade as cellulose acetate, casein, pyroxylin, acrylic urea, phenolic plastics, the device may function as a window for visibility therethrough and to fully close the window opening. Ordinary shutter construction will not accomplish these results.

Having described my invention, I claim:

1. A shutter of the character described including a row of parallel louver blades disposed in a single plane when in closed position; a frame

including side pieces extending across the opposite ends of said blades; means pivotally supporting said blades at their ends to said side pieces to permit the swinging of said blades on said pivots to and from closed position in which adjacent margins of adjacent blades in said row are in overlapping relation; means connecting said blades for simultaneous swinging on their pivots to and from said position; said last mentioned means and said side pieces being connected by a tongue and groove joint when said blades are in said closed position and the overlapping margins of said adjacent blades being also connected by a tongue and groove joint when said blades are in said closed position.

2. In a construction as defined in claim 1, said last mentioned means being connected with said blades by a tongue and groove joint when said blades are in said closed position.

3. A shutter of the character described comprising; a rectangular frame having parallel, vertical side frame members, a sill and a head piece; a row of louver blades extending between said members and disposed in substantially a single plane when in closed position; generally vertically movable strips extending transversely of said blades over one of the sides thereof adjacent their ends; pivots at the ends of said blades mounting the latter on said members for swinging from open to closed position and vice-versa; means pivotally connecting said strips to said blades for so swinging said blades simultaneously; said strips being positioned to extend outwardly of the ends of said blades and across a portion of each of said side members outwardly of the end of said blades; a tongue and a groove respectively formed on the said portion of each side member and on that part of each strip extending over such portion removably fitting one within the other when said strips are moved to swing said blades to closed position and separable from each other when said strips are moved to swing said blades to open position, the said tongue and groove on each such portion and member respectively extending longitudinally thereof.

4. A shutter of the character described comprising; a rectangular window frame having parallel, vertically extending side frame members, a sill, and a head piece; a row of louver blades, extending between said frame members and disposed substantially in a single plane when in closed position; generally vertically movable, vertical strips along the ends of said blades on the sides thereof normally facing into a room in a wall in which said frame is adapted to be positioned; means pivotally connecting said strips to said blades to permit the simultaneous swinging of said blades from said closed position to an open position upon such movement of said strips; means pivotally mounting said blades on said side members for the swinging of said blades; said strips being positioned closely adjacent said side frame members and each having a portion thereof extending oppositely outwardly of the ends of said blades to overlapping relation over a portion of each of said members; grooves formed in the opposite end portions of said blades in vertical alignment when said blades are closed, and a tongue on each of said strips fitting into the said grooves when said blades are in closed position.

5. In a shutter including a rectangular window frame having therein a plurality of horizontally extending adjacent pairs of louver blades dis-

posed one over the other in a single vertical row; pivots at the ends of said blades supporting the blades on said frame for pivoting each blade on its horizontal axis; each of said blades being similarly rabbeted along its opposite longitudinally extending edges at one side only of each blade, thereby providing a marginal portion on each blade of reduced thickness at each side and along each opposite edge thereof; the said blades being supported by their said pivots for movement to closed position in which the blades are disposed in substantially a single plane with the adjacent marginal portions of the adjacent blades of each pair thereof positioned in overlapping, substantially engaging relation with the rabbets in opposed relation; one of each pair of

said adjacent marginal portions being formed with groove centrally of its width opening toward the other marginal portion of such pair and said other marginal portion being formed with a tongue centrally of its width adapted to fit in said groove when said blades are in closed position; the engaging surfaces of each pair of said adjacent marginal portions at opposite sides of the groove and tongue respectively formed therein being flat and in a plane parallel with the plane of each blade, and the longitudinally extending outer edges of each pair of said overlapping marginal portions being substantially in abutting relation to the surface of the shoulder defining one side of each rabbet.

CASIMIR J. WOOD.
